(57) **CLAIM**

The ornamental design for a body fat scale, as shown and described.

DESCRIPTION

FIG. 1 is a front view of the body fat scale showing our new design.

FIG. 2 is a rear view of the body fat scale of FIG. 1.

FIG. 3 is a top view of the body fat scale of FIG. 1.

FIG. 4 is a bottom view of the body fat scale of FIG. 1.

FIG. 5 is a left side view of the body fat scale of FIG. 1.

FIG. 6 is a right side view of the body fat scale of FIG. 1.

FIG. 7 is a top, front, and right perspective view of the body fat scale of FIG. 1; and,

FIG. 8 is a rear and bottom perspective view of the body fat scale of FIG. 1.

The ornamental design which is claimed is shown in solid lines in the drawings. The shade lines in the figures show contour, not surface ornamentation and form no part of the claimed design.

1 Claim, 5 Drawing Sheets
